UNITED STATES PATENT OFFICE.

JOHN F. PETERS, OF ROCHESTER, NEW YORK, ASSIGNOR TO AMERICAN CAN COMPANY, OF NEW YORK, N. Y., A CORPORATION OF NEW JERSEY.

SCORING MACHINE.

Application filed January 11, 1924. Serial No. 685,628.

My invention relates to scoring machines adapted to operate upon sheet metal blanks prior to the formation of a container body, or the like, therefrom.

5 In accordance with present practice in the can making art, it is frequently required to perform a plurality of scoring operations upon the blank and preferably, also, a smoothing operation to remove any irregularities in the metal surface which may have been caused by the scoring rollers. For example, containers provided with a side tearing strip require parallel score lines setting off a tearing strip, and it is also desirable to 10 provide diagonal supplemental parallel, or herringbone, score lines between the parallel lines for the purpose of insuring the tearing of the strip along said parallel lines. It was formerly the practice to perform the 15 different scoring operations in different machines, but prior to my invention certain machines have been developed for performing a plurality of scoring operations upon an individual blank. In the machines of 20 which I am aware, however, the blank is engaged by different operation rollers at the same time and in such case it is necessary that said rollers be of exactly the same diameter in order to prevent variation in the 25 peripheral speed thereof with resultant variations in the lineal speed imparted to the blank by the different rollers. This causes a dragging action between the scoring elements, seriously affecting the efficiency of 30 operation.

It is the principal object of this invention to provide a multiple operation scoring machine in which the scoring units are so related as to eliminate the dragging action, referred to above, in the event that the rollers of the different units are not of precisely the same diameter. The invention contemplates in this connection the arrangement of different sets of scoring rollers in such spaced relationship that the blank is completely freed from one set before being engaged by another.

A further important feature of the invention is that, with the scoring elements so arranged, the blank may be inspected between operations and removed from the machine, if desired, for this purpose.

Another object is the provision, in a machine of the multiple operation type, of

means for accelerating the lineal speed of the 55 blank as it passes from one set of rollers to the other, thus preventing the possibility of overlapping of successive blanks which might be fed into the machine at one time.

Numerous other objects and advantages of 60 the invention will be apparent as it is better understood from the following description, which, taken in connection with the accompanying drawings, discloses a preferred embodiment thereof.

Referring to the drawings, Figure 1 is a front elevation of a machine in which my invention is embodied, partly broken away for better illustration;

Fig. 2 is a top plan view thereof; Fig. 3 is a sectional view, taken substantially on the line 3-3 in Fig. 2;

Fig. 4 is an end elevation, partially broken away; and

Fig. 5 is a vertical sectional view, taken substantially on the line 5-5 in Fig. 1.

The machine as thus illustrated comprises an elongated bed plate 21 upon which are mounted, in the present instance, three scoring heads 22 carrying scoring rollers and operating mechanism as will be hereinafter described, said bed being supported by suitable legs 23 connected together by tie rods 24.

Each head 22 is provided with a base portion 25 resting upon the bed plate 21 and consists of an upwardly extending body 26 having a web 27 extending rearwardly therefrom and spaced forward walls 28 converging at the top and providing bearings 29 and 31 for a shaft 32 (see Figs. 1 and 5). A feed roller 33 is carried upon each shaft 32, it being understood that there are provided a number of said shafts equal to the number of scoring units in the machine, which number, of course, may be varied in accordance with the number of scoring operations required. The shafts 32 extend rearwardly through bearing portions 34 and 35 in the heads 22 and upon the first shaft 32, i. e., the one at the right in Fig. 1, there is carried a pulley 36 adapted to be driven from any suitable source of power. A supplemental bearing 37 is provided for said shaft in a bracket 38 supported by an extension 39 of the bed plate 21. Upon said first shaft 32, there is mounted a sprocket 41 over which is directed a chain 42 taking also over a sprocket 43 on the adjacent shaft 32. A

second sprocket 44 is provided upon said last-mentioned shaft 32 and drives a chain 45 which in turn drives a sprocket 46 on the third shaft 32. It will be noted that the driven sprockets upon the second and third shafts 32 are of smaller diameter than the driving sprockets on the preceding shafts, this being for a purpose which will herein-after appear.

- 10 Spur gears 47 are carried on the rear ends of the shafts 32 and mesh with gears 48 on shafts 49 arranged above and in parallel relationship to said shafts 32. The shafts 49 have bearings 51 and 52 in the heads 22 and 15 also extend through bearings 53 and 54 in overhanging portions 55 of said heads. Operation rollers 56 are mounted on the forward ends of the shafts 49 and are disposed for rotation in recesses 57 formed in the 20 overhanging portions 55 of the heads 22. Said rollers, of course, may be designed to perform any desired scoring operation, the present machine, however, being adapted for the cutting of the parallel score lines in 25 a tearing strip container and diagonal score lines between the parallel lines, to insure accurate tearing away of the strip. The first operation scoring roller is shown clearly in Fig. 4 and is provided with parallel cutting edges 58. The second operation roller is shown in Fig. 5 and is provided with diagonal cutting edges 59. The third operation roller 56 is, in the present instance, a smoothing roller adapted to flatten out 30 any burrs, or irregularities, caused by the action of the scoring rollers.

- It will be noted that the scoring units are spaced a considerable distance apart and, on this account, the blanks are completely freed 40 from one set of rollers before being engaged by another. For the purpose of feeding the blanks from one unit to another, I provide feeding rollers 61 and 62, the former being mounted upon shafts 63, carrying sprockets 45 64 at their rear ends adapted to be driven respectively by the chains 42 and 45. Said shafts 63 have bearings in brackets 65 extending upwardly from the bed plate 21. The rollers 62 are mounted upon studs 66 50 journaled in bearings 67 extending upwardly from the brackets 65. Chain tightening sprockets 68 are mounted on studs 69 in the ends of arms 71 extending laterally from the rear brackets 65.
- 55 A feed table 72 is supported from the heads 22 by means of arms 73 having tongue and slot connections 74 with projections 75 on the bodies 26, said arms 73 being secured firmly in place by cap screws 76.

- 60 A guide 77 is provided on the rear side of the table 72 and it will be manifest that when the blanks are directed across said table, with the inner edges thereof against said guide, they will be accurately directed 65 between the feeding and operation rollers.

Said table 72 is formed in sections, as shown in Fig. 1, in order to provide a proper length for the desired number of scoring units 22. At the receiving end of the table, I provide an extension 78 supported by a bracket 79 secured to the end of and extending upwardly from the bed plate 21. A feed roller 81 is adjustably mounted on a shaft 82 having bearings in a depending portion 83 of the table 72 and in an arm 84 75 extending laterally from the bearing 87. Upon said shaft 82 is mounted a sprocket 85 adapted to be driven by a chain 86 driven by a sprocket 87 upon the first driven shaft 32.

In practice, the blanks are delivered one 80 at a time onto the table above the feeding roller 81 and are directed between the first set of scoring rollers, being then fed forwardly by said rollers and by the feeding rollers 61 and 62. In order to prevent overlapping of the sheets, due to improper feeding, the rollers of each successive scoring unit are driven at a more rapid rate of speed than those of the preceding unit, this being accomplished by the relative size of the driving and driven sprockets on the shafts 32, as hereinbefore described.

It is thought that the invention and many of its attendant advantages will be understood from the foregoing description, and it 95 will be apparent that various changes may be made in the form, construction and arrangement of the parts, without departing from the spirit and scope of the invention, or sacrificing all of its material advantages, the form hereinbefore described being merely a preferred embodiment thereof.

I claim:

1. A scoring machine, comprising a plurality of successive scoring units constructed for cutting only part way through sheets of metal and disposed in such spaced relationship as to permit a blank to be freed from one unit before being engaged by another, and blank-feeding means for directing the blanks to said scoring units and arranged between each scoring unit and the next succeeding scoring unit.

2. A scoring machine, comprising a plurality of successive sets of scoring rollers constructed for cutting only part way through sheets of metal and disposed in such spaced relationship as to permit a blank to be freed from one of said sets of rollers before being engaged by another set, and blank-feeding means for directing the blanks while disengaged from the preceding and succeeding scoring rollers, to said sets of scoring rollers.

3. A scoring machine, comprising a plurality of sets of scoring rollers constructed for cutting only part way through sheets of metal and disposed in such spaced relationship as to permit a blank to be freed from one of said sets of rollers before being en- 125

gaged by another set, and means for feeding the blanks during the scoring operation and from one set of scoring rollers to another.

4. A scoring machine, comprising a plurality of sets of scoring rollers constructed for cutting only part way through sheets of metal and disposed in such spaced relationship as to permit a blank to be freed from one of said sets of rollers before being engaged by another set, and means for feeding the blanks during the scoring operation and from one set of scoring rollers to another, said means comprising feeding rollers disposed beneath the scoring rollers and feeding rollers disposed intermediate said scoring rollers.

5. A scoring machine, comprising a plurality of rollers constructed for cutting only part way through sheets of metal and adapted to successively perform different operations on a blank, said rollers being so related that a preceding operation is completed before a later one is begun, and feeding rollers between preceding and succeeding operation rollers.

6. A scoring machine, comprising a plurality of rollers constructed for cutting only part way through sheets of metal and adapted to successively perform different operations on a blank, said rollers being so related that a preceding operation is completed before a later one is begun, and feeding means associated with each operation roller, and feeding means between said operation rollers.

7. A scoring machine, comprising a plurality of rollers constructed for cutting only part way through sheets of metal and adapted to successively perform different operations on a blank, said rollers being so re-

lated that a preceding operation is completed before a later one is begun, and feeding means associated with each operation roller, said feeding means comprising rollers having progressively accelerated speed of rotation.

8. A scoring machine, comprising a plurality of rollers adapted to successively perform different operations on a blank, said rollers being so related that a preceding operation is completed before a later one is begun, and feeding means associated with each operation roller, said feeding means comprising rollers having progressively accelerated speed of rotation and feeding rollers arranged between the different operation rollers.

9. A scoring machine, comprising a plurality of rollers adapted to successively perform different operations on a blank, said rollers being so related that a preceding operation is completed before a later one is begun, and feeding means associated with each operation roller, said feeding means comprising rollers having progressively accelerated speed of rotation and feeding rollers arranged between the different operation rollers and in advance of the first thereof.

10. A scoring machine, comprising a plurality of spaced scoring units constructed for cutting only part way through sheets of metal, each unit including a feeding roller, shafts upon which said rollers are mounted, and means for driving each successive shaft more rapidly than the preceding one to accelerate the travel of the blanks from station to station through the machine.

JOHN F. PETERS.
